CLAIM

The ornamental design for a foldable felt board, as shown and described.

DESCRIPTION

FIG. 1 is a front, top, right side perspective view for a foldable felt board, showing my new design;

FIG. 2 is a rear, bottom, left side perspective view of FIG. 1 thereof;

FIG. 3 is a front elevational view of FIG. 1 thereof;

FIG. 4 is a rear elevational view of FIG. 1 thereof;

FIG. 5 is a left side elevational view of FIG. 1 thereof, the right side elevational view being a mirror image;

FIG. 6 is a top plan view of FIG. 1 thereof;

FIG. 7 is a bottom plan view of FIG. 1 thereof;

FIG. 8 is a front, top, left side view of FIG. 1 thereof, showing the felt board in partially folded position; and,

FIG. 9 is a front, top, left side view of FIG. 1 thereof, showing the felt board in completely folded position.

1 Claim, 9 Drawing Sheets
